UNITED STATES PATENT OFFICE.

BENJAMIN F. FORTINER AND JAMES G. MAIN, OF PHILADELPHIA, PENNSYLVANIA,
ASSIGNORS TO THE HALE AND KILBURN MANUFACTURING COMPANY, OF PHILA-
DELPHIA, PENNSYLVANIA, A CORPORATION OF PENNSYLVANIA.

CUSHION.

1,143,182.

Specification of Letters Patent. Patented June 15, 1915.

Application filed April 4, 1908. Serial No. 425,129.

To all whom it may concern:

Be it known that we, BENJAMIN F. FORTINER and JAMES G. MAIN, citizens of the United States, residing at Philadelphia, in 5 the county of Philadelphia and State of Pennsylvania, have invented certain new and useful Improvements in Cushions, of which the following is a specification.

This invention concerns cushions adapted 10 particularly for use in the construction of seats for railway cars.

The invention is of particular utility in the construction of cushions for use as backs of car seats, but is also applicable to seat 15 cushions for car seats and cushions for other uses.

The object of the invention is to effect certain improvements in the construction of such cushions with respect particularly to 20 the methods of applying the upholstery and covering material to the frames of the cushions whereby greater strength and superior wearing qualities are obtained and the cost of manufacturing the cushions reduced.

The frame of the cushion constructed in accordance with the invention is made of metal so that it shall be practically fire-proof, sheet-metal parts pressed to the desired form being employed to a very large extent as in this way low manufacturing cost 30 together with ample strength are obtained. In such metallic frame cushions, much difficulty has been experienced heretofore in applying the upholstery and covering material to the metallic frame and securing it firmly thereto so that the upholstery will not shift its position and the cushion will not show wear over a long period of use.

40 One of the objects of our invention is to provide an improved method of applying the upholstery and covering to the frame whereby the requisite strength is obtained and reduction in the cost of manufacture 45 effected. The cushion of our invention is adapted particularly for use as a back cushion in a car seat and, when so used, is supported upon supporting levers which enter sockets formed at the bottom of the 50 side edges of the cushion and from which the cushion may be readily withdrawn for cleaning or repairing. Our invention also includes an improved method of securing the covering material of the cushion about these

sockets for the back-supporting levers permitting the edges of the covering to be quickly secured to the frame in such manner that they are held securely and concealed.

The preferred embodiment of our invention is illustrated in the accompanying drawings in which—

Figure 1 is an elevation of the cushion broken away in part to show the construction, Fig. 2 is a transverse section on line 2—2 of Fig. 1, Fig. 3 is an enlarged sectional view of a portion of the cushion, Fig. 4 is an enlarged sectional view on line 4—4 of Fig. 1 and Fig. 5 is a detail view hereinafter referred to.

Referring to these drawings, the frame of the cushion is of rectangular form and consists of frame members of pressed sheet-metal secured together at their ends. Preferably the frame consists of two such members 1 and 2, the latter being bent to form three sides of the rectangular frame. Each of these frame members is pressed to provide a groove 3 on the outer side thereof and integral flanges 4 at the lateral edges turned inwardly of the frame. Certain of these flanges may be curved in the direction of their length, as shown in Fig. 2, so that the covering material of the cushion overlying these flanges is thereby given the curvature desired for the surface material of the cushion. In order to secure the adjacent ends of the two frame members together metallic corner-pieces 5 are provided to which the ends of the frame members are secured in any suitable manner. These corner-pieces 60 are castings each having two walls lying at right angles one to the other and gussets 6 to contribute to their strength. In order to reinforce the frame at the corners formed by the bends in the member 2, braces 7 are provided consisting of sheet-metal strips pressed to provide flanges at their lateral edges, these flanges being riveted to the flanges formed on the frame member 2. The grooves 3 in the frame members 1 and 2 form a 100 groove extending entirely around the outer side of the frame and having strips 8 of wood, or other suitable material, secured therein, except at the lower portions of the sides of the frame for a purpose hereinafter 105 explained. A central brace 9 formed of sheet-metal extends across the frame and has its ends secured to opposite sides thereof.

A plurality of flat metallic springs 10 extend across the frame perpendicular to the brace 9 and their ends are riveted to the inwardly turned flanges 4 on the frame members 1 and 2. These flat springs are yieldingly sustained by a plurality of spiral springs 11 which lie between the flat springs 10 on opposite sides of the cushion and between those springs and the brace 9.

In order to secure the upholstery and covering material of the cushion to the frame, strips of wood in addition to those located in the grooves 3 are employed, these strips being preferably covered with canvas.

These canvas-covered strips 12 are secured to the flanges 4 on the frame members 1 and 2, so that on each side of the frame a continuous tacking strip is provided extending entirely around the outer edge of the frame.

The strips 12 may be held in place by rivets 13 securing them to the flanges 4. In cushions of this type it is usual to provide an inner covering of fabric termed the "first canvas", over this the upholstery, and then the outer covering which may be of plush or other suitable material, and if desired, a covering of a suitable material such for instance as muslin may be provided between the upholstery material and the outer covering.

In applying these coverings to the frame, the "first canvas" 14 is drawn over the flat springs 10 on one side of the cushion and its edges are secured to the frame members and to the wooden strips 8 in the grooves 3

therein by glue or otherwise, as shown at 15, Fig. 3. A similar covering 16 is then applied over the flat springs 10 on the other side of the cushion and its edges securely glued to the frame over the edges of the canvas covering 14, as shown at 17, Fig. 3.

An upholstery edging 18 is then applied to each face of the cushion frame extending entirely around the cushion or around the top and side edges only, as desired, the tacking strips 12 forming a foundation and support

for the edging. This edging is secured to the frame by tacks 20 passing through the wooden strips 12, the ends of these tacks engaging the metal underlying the strips 12

and being turned thereby so that they are clenched and held firmly against withdrawal. The hair or other upholstery 21 is then applied over the "first canvas" 14 and 16 and within the area defined by the edging

18. A textile covering 22 is then drawn over the hair 21 and edging 18 on each side of the cushion and the edges of these two coverings are secured to the frame of the cushion in any suitable manner, preferably by a few

tacks driven through the edges of the covering and into the wooden strips 8. The outer covering 23 is then applied over the faces of the cushion and its edges are securely fastened to the frame of the cushion by a line of tacks driven through the edges of the cov-

erings 23, 22, 16 and 14 and into the wooden strips 8. These tacks hold all of the several coverings firmly to the cushion frame and give ample strength to the finished cushion; as they not only hold the edges of the outer

coverings 23 to the frame but also the edges of the coverings 22, 16 and 14, the latter may, in the construction of the cushion, be secured to the frame by glue or by a small number of tacks spaced apart by consider-

able distance, as these securing means are not relied on to hold the inner coverings in the finished cushion. In this way the liability of splitting the strips 8 by the employment of a number of tacks driven into them, is

reduced to a minimum. As above mentioned the strips 8 of wood are omitted at the lower portions of the side edges of the frame. At these points the groove 3 formed in the frame member 2 is enlarged and socket mem-

bers 24, U-shaped in cross-section are secured within the enlarged portions of this groove by screws 25 passing through openings in the frame member 2 and entering threaded openings in the corner-pieces 5. These

socket members 24 are employed not only as sockets to receive the back-supporting levers 26 but also to secure the edges of the outer coverings 22 and 23 to the frame; the edges of the coverings 22 and 23 along the

portions of the frame where the wooden strips 8 are omitted, are carried down into the groove 3 in the frame member 2, as shown at 27, Fig. 4. When in this position the socket members 24 are inserted in place

and secured by the screws 25 so that they serve as clamps to hold the edges firmly to the frame. This having been done, covering plates 28 are secured to the side edges of the frame by screws the ends of which enter

threaded openings in the corner-pieces 5 so that these plates with the socket members 24 form openings extending lengthwise of the side edges of the cushion adapted to receive the back-supporting levers 26.

Having described our invention, what we claim as new therein and desire to secure by Letters Patent of the United States is:

1. In a cushion, a frame formed of sheet-metal frame-members secured together at their ends and having the lateral edges thereof turned inwardly of the frame to form flanges extending at substantially a right angle to the body-portions of the members, tacking strips disposed in the plane of the frame, lying flat against the outer sides of said inwardly-turned flanges and secured to the flanges, springs supported on the frame, upholstery material secured to said tacking strips and a covering extending over the frame, yieldingly sustained by said springs and having its edges secured to the frame, substantially as set forth.

2. In a cushion, a frame formed of sheet-metal frame members secured together at

their ends and each pressed to provide flanges at its lateral edges extending inwardly of the frame, wide, thin tacking strips secured to the outer sides of said flanges on both sides of the frame, springs supported by said frame, upholstery material overlying said springs and yieldingly supported thereby on both sides of the frame, and means for securing said material to said strips, substantially as described.

3. In a cushion, a frame formed of sheet-metal frame-members secured together at their ends, said members having grooves in the outer sides thereof and integral flanges extending inwardly of the frame at the edges of the members, tacking strips in said grooves, tacking strips disposed in the plane of the frame, lying flat against said flanges and secured to the outer sides of the flanges, springs supported on said frame, upholstery material secured to the tacking strips on said flanges and a covering for the cushion yieldingly sustained by said springs and having its edges secured to the tacking strips in said grooves, substantially as set forth.

4. In a cushion, a frame formed of sheet-metal frame members secured together at their ends and pressed to provide flanges extending inwardly of the frame, tacking strips disposed in the plane of the frame, lying against said flanges and secured to the flanges, springs supported on said frame, upholstery material extending over said springs and yieldingly sustained thereby, and tacks securing said material to said strips, said tacks extending through said strips and having their ends turned by said flanges, substantially as described.

40 5. In a cushion, a frame formed of sheet-metal frame members secured together at their ends and pressed to provide flanges extending inwardly of the frame, tacking strips disposed in the plane of the frame, lying against said flanges and secured to the flanges, springs supported on said frame, strips of upholstery secured to said tacking strips, upholstery overlying said springs, a covering extending over said upholstery and means for securing the edges of the covering to the frame, substantially as described.

55 6. In a cushion, a frame formed of sheet-metal frame members secured together at their ends and pressed to provide grooves on the outer sides thereof, tacking strips in said grooves, springs supported on said frame, inner and outer coverings extending over the same side of said frame, means for se-

curing the edges of said inner covering to 60 said frame, and tacks entering said tacking strips and securing the edges of both said coverings to said frame, said tacks forming a securing means for the inner covering independent of and additional to the securing 65 means above named, substantially as described.

7. In a cushion having upholstery on both sides thereof, a frame formed of sheet-metal frame-members secured together at their 70 ends, said members having grooves in the outer sides thereof and integral flanges extending inwardly of the frame at the edges of the members, tacking-strips in said grooves, thin tacking-strips disposed in the 75 plane of the frame, lying flat against said flanges on both sides of the frame and secured to the outer sides of the flanges, springs supported by said frame, canvas members on both sides of the cushion drawn 80 over said springs and secured to the tacking-strips in the grooves, upholstery material positioned outside said canvas members and secured through the same to the tacking-strips on said flanges, and a covering for 85 the cushion, positioned outside of said members and upholstery material, and having its edges secured to the tacking-strips in said grooves, substantially as set forth.

8. In a cushion, a frame formed of sheet- 90 metal frame-members secured together, pressed to provide a groove on the outer side thereof and integral flanges turned inwardly of the frame, a tacking-strip in said groove, thin tacking-strips lying flat against 95 the outer sides of both of said flanges, flat metal springs extending across the frame with their ends disposed against the inner sides of the said flanges, rivets securing said thin tacking-strips and springs to said 100 flanges, canvas members on both sides of the cushion drawn over said springs and secured to the tacking-strip in the groove, upholstery material secured by tacks through said canvas members to the tacking- 105 strips on the flanges, and a covering for the cushion, positioned outside said members and upholstery material and secured to the tacking-strip in the groove, substantially as set forth.

P. J. TUCKER.

It is hereby certified that in Letters Patent No. 1,143,182, granted June 15, 1915, upon the application of Benjamin F. Fortiner and James G. Main, of Philadelphia, Pennsylvania, for an improvement in "Cushions," an error appears in the printed specification requiring correction as follows: Page 3, lines 4-5, strike out the words "secured to the outer sides of said flanges on both sides of the frame," and insert the words *disposed in the plane of the frame and lying against the outer sides of said flanges on both sides of the frame secured to the flanges*; and that the said Letters Patent should be read with this correction therein that the same may conform to the record of the case in the Patent Office.

Signed and sealed this 6th day of July, A. D., 1915.
